HYDRAULIC PUMP OR MOTOR

Harry L. Chisholm, Jr., Buffalo, N. Y., assignor to
Houdaille-Hershey Corporation, Detroit, Mich.,
a corporation of Michigan

Application May 8, 1942, Serial No 442,146

3 Claims. (Cl. 103—123)

My invention relates to hydraulic devices, particularly of the rotary type, which can be operated with equal efficiency to function as a pump or as a motor. My invention is particularly applicable to hydraulic structures such as disclosed in my copending application United States Serial No. 437,334, filed April 2, 1942. The hydraulic structure in this pending application is operable either as a rotary pump or as a rotary hydraulic motor, but only with one direction of rotation of the rotor element, so that the structure is not reversible.

An important object of my present invention is to adapt structures of the type referred to for reversibility when operated either as a hydraulic pump or as a motor.

A further object is to provide improved construction and control of the rotor engaging blades for adapting the structure for equally efficient forward or reverse operation.

A further object is to provide simple valving means for controlling the direction of fluid flow through the rotor for either forward or reverse operation.

Another object is to provide means controlled by the valving structure for subjecting the rotor engaging blades to differential pressure cooperable with spring means engaging the blades so that the pressure engagement of the blades with the rotors will be substantially constant under all pressures of the fluid flow through the structure and with minimum friction so as to avoid loss of energy and efficiency particularly during starting of the structure as a pump or as a motor.

The various features of my invention are embodied in the structure shown on the accompanying drawings, in which drawings:

Figure 1 is a plan view of the hydraulic structure;

Figure 2 is a section on plane II—II of Figure 3;

Figure 3 is a section on plane III—III of Figure 2;

Figure 4 is a section on plane IV—IV of Figure 2;

Figure 5 is an enlarged sectional view of one of the blade structures shown on Figure 3;

Figure 6 is a section on plane VI—VI of Figure 5 showing the blade in its upper position; and

Figure 7 is an enlarged transverse section of the fluid flow controlling valve.

The structure shown comprises the cylindrical housing wall 10 having the inner wall or head

11 integral therewith. On the other end of the housing a head 12 is provided whose flange 12' fits into the housing end and between which and the head 11 are clamped the various elements 5 which form the pump cylinder, the clamping being effected by a ring 13 threading into the end of the wall 10. A shaft 14 extends into the housing and is journaled in ball bearings 15 and 16 supported respectively by the head 11 and the head 12, the shaft extending outwardly from the head 11 for mounting, or connection with, a driving source, such as an electric motor, when the structure is used as a pump, or with devices to be driven when the structure is operated as a motor. A fitting 17 receives the shaft and is secured as by bolts 18 to the head 11 and may serve as a bracket for supporting the hydraulic structure. The fitting 17 engages a washer 19 for compressing packing 20 around the shaft to prevent leakage.

The pump cylinder forming elements comprise two rings 23 and 24, an inner plate 25, an intermediate plate 26, and an outer plate 27, the outer diameters of the rings and plates being such that they will fit snugly in the cylindrical bore of the wall 10 to be clamped between the heads 11 and 12 by the clamping ring 13. The rings and plates define annular cylindrical spaces 28 and 29 into which the rotor elements 30 and 31 extend for rotation by the shaft 14 to which they are secured as by keys 32. The pump may have any number of rotors and rings, two sets being shown.

The rotor elements 30 and 31 are of generally elliptical or oval shape so as to define with the cylinder space walls crescent-shaped working chambers. The rotors are displaced 90° on the shaft 14 so that the opposite working chambers 33 and 34 between the rotor 30 and the ring 23 35 will have their maximum volumetric displacement when the working chambers 35 and 36 between the rotor 31 and the ring 24 have their minimum volumetric displacement.

For the cylinder spaces 28 and 29, in which the rotors operate, diametrically opposite fluid inlet passageways *s* and *s'* and diametrically opposite fluid discharge passageways *d* and *d'* are provided. To form these passageways, the rings 23 and 24 have transverse bores 41 therethrough which align with the bores 42 in the plates 26 and 27. The inlet passageways *s* and *s'* communicate with the cylinder spaces through ports 39 and 39', while the passageways *d* and *d'* communicate with the cylinder spaces through ports 40 and 40' (Figure 2). At their inner ends the

inlet and outlet passageways are closed by the plate 25.

The rings 23 and 24 are each provided with diametrically opposite blades 43 and 43' for co-operating with the rotors surrounded by the rings, the blades operating in radially extending slots or chambers 44 and 44' respectively, the blades 43 being located between the inlet passageway s and the outlet passageway d, while the blades 43' are located between the inlet passageway s' and the outlet passageway d'. Engaging the outer end of each blade is a plunger or piston 45 slideable in a passageway 46 extending radially through the corresponding rings 23 and 24. The plunger is cylindrical and bored to receive a spring 47 which extends outwardly into a plug 48 secured to the housing wall 10. The pressure of the springs 47 tends to keep the blades seated with their inner ends against the respective rotors.

The head 12 of the hydraulic structure has the cylinder bore 49 therethrough forming a valve chamber for a valve v. This valve has a central passageway therethrough for the end of the valve stem 50 to which it is secured, this stem extending outwardly beyond the outer end of the head 12 and terminating in a grip 51, a packing box 52 preventing leakage. Other passageways 53 extending longitudinally through the valve provide for flow of fluid from one end of the valve chamber to the other. The valve has the annular port 54 which, when the valve is in its inner position shown in Figure 3, spans the inner annular port 55 and the intermediate annular port 56 formed in the head 12, and when the valve is in its outer position as shown in Figure 4, the valve port spans the intermediate port 56 and the outer annular port 57 in the head 12. As shown on Figures 1 and 3, the flow passageway 58 in the head 12 communicates with the outer end of the valve chamber and a flow passageway 59 through the head communicates with the valve chamber at a point between the inner and outer ports 55 to 57 and in line with the intermediate port 56 in the head 12.

The inner port 55 in the head 12 is connected by a passageway 60 (Figure 3) with the outer end of the pump discharge passageway d, and similar passageway 61 (Figure 4) connects the port with the pump passageway d'. The outer port 57 in the head 12 is connected by a passageway 62 (Figure 4) with the pump inlet passageway s, and a similar passageway 63 (Figure 3) connects the port 57 with the pump inlet passageway s'.

When the structure is to be operated as a pump, the passageway 58 in the head 12 will be the inlet for fluid to be drawn from a source of supply such as a reservoir, and the passageway 59 in the head 12 will be the discharge outlet for the pump. Referring to Figure 3, with the valve v in its inner position for spanning the head ports 55 and 56, the pump is rotated by the motor in counter-clockwise direction (Figure 2). The fluid will now be drawn in through the inlet 58 into the outer end of the valve chamber and into the outer port 57 in the head 12 and from there through the passageways 62 and 63 into the pump passageways s and s', the fluid being delivered from the pump under pressure by way of the passageways 60 and 61 in the head 12 to the inner head port 55 and through the valve port 54 and out through the outlet 59 (Figure 1). If the direction of rotation of the pump is to be reversed to be clockwise, the valve v is shifted to its outer position shown in Figure 4. The fluid drawn into

the inlet 58 will now flow through the valve passageways 53 to the head port 55 and from there through the passageways 60 and 61 into the pump passageways d and d', the fluid being discharged from the pump under pressure through the passageways 62 and 63 into the outer head port 57 and then through the valve port 54 and out of the outlet passageway 59.

If it is desired to operate the hydraulic structure as a motor, the passageway 59 in the head 12 is connected with a source, such as a pump, which delivers fluid under pressure. With the valve in its inner position shown in Figure 3, the fluid under pressure will be directed by the valve port 54 to the inner head port 55 and from there through the passageways 60 and 61 to the pump passageways d and d' for engagement with the rotors for clockwise rotation thereof and of the shaft 14, the spent fluid entering the pump passageways s and s' for flow through the passageways 62 and 63 to the outer head port 57 and from there through the passageway 58 back to the reservoir from which the pump receives its fluid supply for producing the pressure flow for driving the hydraulic structure as a motor.

If it is desired to drive the hydraulic structure of the motor in a reverse direction, the valve is shifted to its outer position shown on Figure 4, the fluid under pressure then entering through the passageway 59 to be directed by the valve port 54 to the outer head port 57 and from there through passageways 62 and 63 into the pump passageways s and s' for engagement with the rotors for counter-clockwise rotation thereof, the spent fluid entering the pump passageways d and d' from where it flows through the passageways 60 and 61 to the inner head port 55 and then through the valve passageways 53 to the outer end of the valve chamber for return through the passageway 58 to the reservoir. Thus, by setting of the valve v, the hydraulic structure can be operated in either direction, either as a pump or as a motor.

In order to obtain efficiency, it is very important that the blades be held with their tips in perfect contact with the rotors so as to avoid leakage of fluid directly from the high pressure to the low pressure side, but at the same time the pressure holding the blades against the rotors should be kept constant and with minimum friction between the blades and the rotors, whether the hydraulic structure is operating in either direction as a pump or as a motor. The blades are of flat rectangular shape and are disposed in a radial plane extending through the axis of the cylinder and rotor, and the contact end of each blade is of V cross section for presenting a contact edge to the rotors, the blade ends being symmetrical at each side of the central or contact edge with the slope of the surfaces 64 and 65 at the most efficient angle. As shown, the angle of slope is about 30°. This contact edge is at all times the sole area of engagement of the blade with the rotor. During operation of the structure in either direction, either of the surfaces 64 or 65 will be subjected to the high pressure fluid while the other surface is subjected to the low pressure. This high pressure against the blade ends will tend to shift them outwardly against the resistance of their springs 47, and this outward effort against the blades is always in direct proportion to the pressure of the fluid. I therefore provide means for subjecting the outer ends 76 of the blades at all times to the same hydraulic

pressure per square inch as that of the high pressure acting against either end surface of the blades. Such counteracting pressure against the blades is preferably controlled to be at all times slightly greater than the outward pressure against the blades so that this differential pressure will assist the springs 47 in holding the blades in proper contact with the rotor. From the description thus far it is noted that, while the hydraulic structure is being operated in either direction as a pump or as a motor, the intermediate head port 56 is always subjected to the fluid flow under high pressure, and that, when the structure is operated as a pump, the intermediate port 56 is in connection with the high pressure discharge of the pump, and that, while the structure is being operated as a motor the port 56 is always subjected to the high pressure fluid which operates the structure as a motor.

Referring particularly to Figures 3 to 6, inclusive, a channel 66 is cut in the housing wall 10 in alignment with the passages 46 in which the plungers 45 for the blades 43 operate, and a similar channel (Figure 2) is provided for the plungers for the blades 43. Channels 67 in the outer face of the plate 27 extend from the channels 66 and are connected by passageways 68 and 69 in the head 12 with the intermediate head port 56, as shown in Figures 3 and 4.

The surfaces 64 and 65 at the contact end of each blade are of the same area, and this area is so proportioned to the area of the plunger 45 which is subjected to the counteracting high pressure that the counteracting pressure is sufficiently greater than the outward pressure against the blades so that this pressure differential may assist the spring 47 in holding the blade in proper contact with the rotor. This pressure differential varies in value in direct proportion with the variation in the pressure of the high pressure flow through the structure, thus automatically increasing the force of blade contact as demanded by the operation of the structure. The differential pressure against the blades is made just sufficient so that this pressure together with the springs will hold the blades in leakage preventing contact with the rotors and with minimum friction under all conditions of fluid flow through the structure, whether the structure is operating as a pump or as a motor in either direction.

At their outer ends, the chambers 44 for the blades are connected together by passageways 70 in the plate 26, and through passageways 71 in the plate 25 these chambers communicate with channels 72 in the outer side of the plate 25, which channels lead to the inner space in the structure through which the shaft 14 extends, this space being at all times in communication with the low pressure outlet through the valve passages 53.

The movement of the valve stem 50 for setting of the valve v to its inner or outer positions is limited by the engagement by the grip 51 with the end of the packing box 52, or by engagement of the abutment pin 73 on the stem with the head wall at the outer end of the valve chamber, as shown in Figure 4, these two limits of movement of the stem accurately setting the valve in its inner position shown on Figure 3, or its outer position shown on Figure 4.

I have thus produced a simple hydraulic structure of the type referred to which can operate equally efficiently as a pump or as a hydraulic motor and which, by manipulation of simple valve

mechanism, may be readily reversed. The blades under spring action and differential pressure in cooperation therewith will at all times maintain accurate contact of the blades with the rotors and with minimum friction so as to avoid loss of energy and efficiency particularly during starting of the structure either as a pump or as a motor.

I have shown a practical and efficient embodiment of the features of my invention but I do not desire to be limited to the exact arrangement, construction and operation shown and described, as changes and modifications may be made without departing from the scope of the invention.

I claim as my invention:

1. A hydraulic rotary structure of the type described comprising a housing defining a cylinder space, a rotor of elliptic cross section within said space connected to cooperate with the cylinder space walls to define a working chamber, inlet and outlet ports for said working chamber, a flat rectangular blade between said ports disposed in a radial plane extending through the axis of said cylinder space and rotor, a chamber in said housing for said blade, spring means urging said blade into contact with said rotor, a valve chamber in said housing, a fluid inlet and a fluid outlet for said valve chamber, passageways connecting said valve chamber with the ports for said working chamber, a valve in said valve chamber adapted for setting to control the direction of the fluid flow from said valve chamber through said ports and working chamber, said blade at its contact end being of V-shape cross section to provide a contact edge engaging said rotor surface and sloping surfaces at opposite sides of said edge of the same area, said contact edge alone being at all times the sole area of engagement of the blade with the rotor, one of said surfaces being exposed to the high pressure of the fluid flow during operation of the structure tending to shift the blade longitudinally outwardly against the force of said spring means, a piston abutting said blade but otherwise disconnected therefrom, a high pressure flow passageway between said valve chamber and said piston and means whereby setting of said valve for either direction of operation of said structure will connect said high pressure flow passageway to the piston for flow of high pressure fluid against the piston for counteracting the outward pressure on said blade, the area of the piston exposed to the fluid pressure being only slightly greater than the area of the surface at the contact end of the blade exposed to the high pressure whereby a slight differential pressure on the blade will assist said spring means in holding the blade in contact with the rotor.

2. A hydraulic rotary structure of the type described comprising a housing defining a cylinder space, a rotor of elliptical cross section within said space to cooperate with the cylinder space wall to define a working chamber, inlet and outlet ports for said working chamber, valve means adapted to be set to control the direction of fluid flow through said structure for operation thereof in either direction as a motor or as a pump, a flat rectangular abutment blade for the rotor operable in a radial plane extending through the axis of said cylinder space and rotor, a guide slot for said blade and a wall closing the outer end of said slot, the contact end of said blade being of V-shaped cross-section

to define a contact edge and opposite sloping surfaces of equal area, said contact edge alone being at all times the sole area of engagement of said blade with said rotor, one of said surfaces being subjected during operation of the structure to the high pressure fluid flow therethrough tending to shift the blade longitudinally away from the rotor, said slot closure wall having a bore therethrough and a cup-shaped piston movable in said bore for abutting engagement with the outer end of said blade, a spring extending into said piston tending to urge said piston against said blade to hold the blade with its contact edge against the rotor, and a passageway in said housing open during either setting of said valve means for conducting high pressure fluid flow against said piston whereby said piston will assist said spring in holding the blade in contact with the rotor, the area of the piston subjected to said pressure being only slightly greater than the area of the surface of the contact end of the blade subjected to the high pressure flow whereby only a slight differential fluid pressure of the blade will assist the spring in holding the blade in contact with the rotor with minimum friction engagement.

3. A hydraulic rotary structure of the type described comprising a housing defining a cylinder space, a rotor of elliptical cross section within said space to cooperate with the cylinder space wall to define a working chamber, inlet and outlet ports for said chamber, valve means adapted to be set to control the direction of fluid flow through said structure for operation thereof in either direction as a motor or as a pump, a flat rectangular blade disposed in a radial plane ex-

tending through the axis of said cylinder space and rotor, the contact end of said blade being of V-shape cross section to define a contact edge engaging said rotor and opposite sloping surfaces of equal area, said contact edge alone being at all times the sole area of engagement of said blade with said rotor, one of said surfaces being subjected during operation of the structure to the high pressure fluid flow therethrough tending to 10 shift the blade longitudinally away from the rotor, a guide slot for said blade and a wall in the upper end of said slot, a bore through said wall, a cup-shaped piston movable in said bore for abutting engagement with the outer end of said blade 15 but otherwise disconnected from said blade whereby said blade may freely operate in said slot without interference by said piston, a spring extending into said piston for holding the piston abutted against the blade for engagement of the 20 contact edge of the blade with the rotor, and a passageway in said housing open during either setting of said valve means for conducting high pressure fluid flow against said piston for movement of said piston to assist said spring in holding 25 the blade in contact with the rotor, the area of the piston subjected to said fluid pressure being so proportioned to the area of the surface of the contact end of the blade subjected to the high pressure whereby only a slight differential 30 fluid pressure on the blade will assist the spring in holding the blade in contact with the rotor with minimum friction between the blade and rotor when the rotor is operating.
